UNITED STATES PATENT OFFICE

EMIL OTTO KNISCHEWSKY, OF HAMILTON, ONTARIO, CANADA

HOCKEY PAD

Application filed February 27, 1929. Serial No. 343,141.

My invention relates to improvements in 5
hockey pads, shin guards, and the like, and
the object of my invention is to construct a
guard or pad which will deaden any heavy
blows that are received thereon and so effec-
tively protect the wearer.

A further object of my invention is to so
form my pad that the filling or packing there-
in is held against creeping within the pad
10 so that there is no possibility of such pack-
ing becoming lumped after the pad has been
in use for some little time, and a still fur-
ther object of my invention is to so design
my pad that it can be manufactured for the
15 same cost as the standard pad now being
made.

My invention consists of a pad or shin
guard constructed and arranged all as here-
inafter more particularly described and il-
lustrated in the accompanying drawings in
20 which:

Fig. 1 is a front elevational view of my
pad, part of the protective covering being
25 broken away.

Fig. 2 is a rear elevational view of my pad,
part of the rear face thereof being broken
away.

Fig. 3 is a horizontal cross sectional view
30 taken through the line 3—3, Fig. 2, and

Fig. 4 is a horizontal cross sectional view
taken through the line 4—4, Fig. 2.

Like characters of reference indicate cor-
responding parts in the different views.

My hockey pad in itself is of the same gen-
eral appearance and shape as the standard
pad, and comprises a shin protecting portion
1 formed of spaced apart vertical canes, and
a knee protecting portion 2 formed with a
40 knee cap receiving recess 3 which is made of
fibre or other similar material. As the knee
protecting portion, however, forms no part
of the present invention it is not necessary to
specifically describe its construction.

In constructing the shin protecting por-
tion of my guard, I first cut a piece of felt
into substantially the shape of the felt 4 il-
lustrated in Figs. 1 and 2 of the drawings. I
next form my cane guard from a plurality of
50 split canes 5 which are inserted into a plu-

rality of parallel sleeves or pockets 6 formed by
an outer layer of leather 7 and an inner layer
of fabric 8, rows of parallel stitching 9 ex-
tending between the leather and the fabric to
form the pockets.

The cane guard portion is formed of the
same shape as the shin protective portion of
the felt 4 though being of a slightly smaller
size as can be seen upon reference to Fig. 1.
When the cane guard portion is completed by
60 inserting the canes 5 into the pockets 6 such
portion is laid centrally upon the pad 4 and
sewn thereto by a line of stitching 10 which
runs around the edge of the cane guard from
one upper corner, down the side, across the
65 bottom, and up the other side to the other
upper corner which at this stage of the con-
struction leaves the top edge open.

A piece of felt 11 which is approximately
the same length as the width of the bottom of
the pocket formed between the cane guard
and the felt is inserted between the cane guard
and the felt so that it extends across the bot-
tom 12 of such pocket.

The pocket is then padded or filled with
70 cotton wool 13 so that such filling forms a
soft thick layer between the felt 4 and the
cane guard and extends from the top of the
felt insert pad 11 to the vicinity of the top
open end of the pocket.

A piece of felt 14 of a length substantially
equal to the width of the top of the pocket
is then inserted so that it extends there-
across, and the top of the pocket is then sewn
across by the line of stitching 15. For re-
taining the cotton wool filler 13 in place so
that it does not become lumped I insert sev-
eral spaced apart rows of stitching 16 which
extend down the pad between the canes.
These rows of stitching are put in by hand
80 with strong thread and extend through the
leather facing 7, fabric 8, and felt 4, thus
effectively retaining the cotton filler in place.

The provision of the felt pads 11 and 14
90 is an improved feature in my construction as
they are particularly effective in deadening
the impact of a blow upon any part of the
pad. If these felt inserts were not posi-
tioned in the bottom and top of the pocket
it would be necessary to fill such top and bot-
95 100

tom spaces with the cotton wool which would not positively space the ends of the canes away from the felt 4 as it would be practically impossible to fill the pocket with cotton wool without having any tapering of the filler at the top and bottom of the pocket, it being practically certain that the ends of the canes would lie very closely to the felt 4. If such pads 11 and 14 were not provided the tops and bottoms of the canes 5 would in all probability, after a little usage, rest against the felt shin guard portion 4 and as such canes would be lying directly upon the cotton filler any severe blow would be transmitted from the canes through the cotton filler to the legs of the wearer.

By the provision of the upper and lower pads 11 and 14 I furnish an extra support for the canes as their ends rest upon the pads thus preventing them directly resting upon the cotton filler, and when a blow is received intermediately of the length of the canes, the canes being supported at their ends by the pads 11 and 14 will bend inwardly under the force of the blow and such bending movement will be taken up by the cotton filler. It will be thus seen that by supporting the guard canes at their tops and bottoms that I have provided a means whereby such canes are spaced away from the filler and which will effectively prevent the force of the blow from being transmitted therethrough.

From the foregoing description it will be apparent that I have devised a simple and efficient type of hockey pad which will afford the wearer the maximum of protection against any blows that may be received in the course of play, and although I have shown and described a particular embodiment of my invention it is to be understood that I can make such changes and alterations as I may deem necessary without departing from the spirit of my invention as set forth in the appended claim.

What I claim as my invention is:

In a pad of the character described an inner felt portion, an outer portion having a plurality of vertical pockets therein and stitched around its edge to the inner felt, a plurality of canes contained in said pockets, a pair of upper and lower felt inserts positioned between the outer portion and the inner felt so that the ends of the canes rest upon the inserts, a cotton wool filler contained between the outer portion and the inner felt and extending between the inserts, and a plurality of rows of stitching extending between the felt inserts, and passing through the outer portion, the cotton filler and inner felt.

In witness whereof, I hereunto set my hand
EMIL OTTO KNISCHEWSKY.
